UNITED STATES PATENT OFFICE

DELMER LAMIN, OF LOS ANGELES, CALIFORNIA

METAL BOAT CONSTRUCTION

Application filed July 17, 1928. Serial No. 293,470.

This invention relates to the art of ship building and is more particularly a method for constructing metal boats or ships in which the use of rivets or other fastening means are substituted by welding joints and in which novel means are used for positioning the relative members of such a construction without the ordinarily employed casting and forging or hot bending operations.

10 It is a particular object of this invention to develop a process whereby the members of a boat or ship may be placed in position to conform to the contour of a cubic parabola which has been found to be one of the most efficient forms of stream line construction. It will be understood however, that boats may be constructed by this process having any desired shape of stream line, such construction being dependent entirely upon the

15 design of the vessel.

It is a further object of this invention to develop a process in which the fabrication of the boat is done entirely by welding, there being no rolling or stamping of the shell plates. These members are cut in sections and are applied directly by pressure against cells in the frame work which are formed by a system of transverse and longitudinal rib members, such members being secured to one

20 another and the transverse members being secured to the keel by means of welding. The longitudinal rib members are cold bent about the transverse rib members and are preferably received by suitably formed recesses in the last mentioned members.

It will be understood that the process has a further object of greatly decreasing the cost of boat construction since the forging or rolling or stamping operations are eliminated, and the placement of rivet holes and the riveting of the respective parts which is a large factor in the expense of boat construction, are also eliminated.

Other objects and advantages in this method of boat construction will be better

understood from the following description of an illustrative embodiment of a vessel constructed by this method as shown in the accompanying drawings, in which

Fig. 1 illustrates the body of a boat such as may be constructed by the herein described process.

Fig. 2 is a plan view illustrating the frame work of a boat such as may be constructed by the process herein described.

Fig. 3 is a sectional elevation taken substantially in a plane represented by the line 3-3 in Fig. 2.

Fig. 4 is an enlarged perspective view showing a portion of the frame work of a boat such as is illustrated in Fig. 1 and demonstrating the manner of arranging and placing the respective parts or sections.

Fig. 5 is an enlarged sectional view which may be considered as having been taken substantially in a plane by the line 5-5 in Fig. 4.

Fig. 6 is an enlarged sectional view which may be considered as having been taken in a plane indicated by the line 6-6 in Fig. 4.

Fig. 7 is a plan view illustrating a preferred manner of forming the transverse rib members.

More particularly describing the invention as herein illustrated reference numeral 11 indicates a metal boat of the type herein described which has a keel 12 and side plating 13. It will be understood while this invention is described in connection with a small craft that it is not confined to any particular size or type of vessel and although in the vessel herein described the keel 12 is illustrated as supporting directly the transverse ribs indicated by reference numeral 14, these ribs may, in a larger type of vessel be secured to the keelsons.

The ribs 14 may be formed in any desired manner and it will be understood that their curvature and strength are determined by the design of the vessel. I have found in the

development of this method that most satisfactory results are economically obtained by using substantially flat metal bars which may be bent upon a bending floor to conform to the design or lay out of the transverse members, or which may be cut from metal plates as indicated in Fig. 7, in which case the pattern or design which is laid out by the designer of the vessel, is marked out upon the flat metal sheet 14, such marking being indicated by reference numeral 15, and the transverse ribs 14 are cut therefrom by means of an acetylene torch or any other suitable cutting mechanism commonly known to those familiar with the art.

After the transverse members have been formed, they are provided with a series of notches indicated by reference numeral 16, the position of such notches being also calculated by the designer of the vessel and being arranged in alignment throughout the length of the transverse ribs.

The transverse ribs are then placed in position upon the keel as indicated in the perspective view shown in Fig. 4 and are secured to the keel which may be in a form of united channel irons or an I beam, by means of welding such welding being indicated by reference numeral 18 on Fig. 4.

After the transverse ribs have been placed in position, the longitudinal ribs 19 are attached thereto by taking substantially straight and flat metal bars, welding one end of such bars to one of the end transverse members such as is indicated at 20 in Fig. 2, and by means of a windlass or by any other suitable power applying means, these bars, forming the longitudinal members are bent throughout the respective positions illustrated in dotted lines of Fig. 2, to be received by the recesses 16 in the transverse ribs and to conform thereby to the designed outline or profile of the vessel.

It will be understood that in bending these longitudinal ribs, it is preferable to weld the bar progressively to each transverse member as the longitudinal bar is brought into engagement with the mentioned recess.

It will be understood by those familiar with the art, that metal such as steel, which is cold bent, assumes during such a bending operation a substantially cubic parabola, the dimensions or outlines of which are dependent upon the magnitude of the bending moment, the cross sectional area of the bar and its bending or elastic strength. It will therefore be apparent to those familiar with the action of metal under such a strain, that the metal which is bent in this manner tends to develop a surface corresponding to a cubic parabola which represents one of the closest approaches to a so-called ideal stream line curvature. Such a system also eliminates the necessity of artificial or hot bending which is costly from the standpoint of labor and requires

skill much greater than demanded in the execution of a process such as is herein described.

After the skeleton or frame work of the vessel has been constructed as described above, the plating or "skin" of the vessel is placed in position in a manner somewhat as follows:

It will be understood that the mentioned system of transverse and longitudinal intersecting rib members forms a plurality of cell spaces or sections each defined by portions of these intersecting rib members as may be indicated by the section defined by members *a, b, c* and *d* in Fig. 4.

It is a comparatively simple matter to outline from these sections or to calculate in the design of the vessel the pattern or form necessary to obtain a uniform covering of such a section from a substantially flat metal plate and from these patterns the mentioned plates are laid off and cut from sheets of metal plating. The plate sections 21, 21', so cut, are attached to the rib members by means of welding.

In such an attachment one edge of the plate is welded to one of the rib members and the plate is then bent to conform to the curvature of the outline of the frame work by means of a plurality of C clamps, such as are indicated at 22 in Fig. 4.

The plate 21 is illustrated as having been placed in position and the plate 21' being held in place preparatory to the welding operation, it will be understood that the C clamps which press the plate to the longitudinal and transverse rib members exercise a double bending moment around the horizontal and vertical axes of the plate and owing to the elasticity of the metal, the plate receives a double deflection.

The horizontal deflection is guided by the run of the longitudinal ribs and the vertical deflection depends upon the thickness of the plate and the magnitude of the curvature of these ribs at the point at which the plate is being applied.

The first factor may be considered as being a constant and the second one as a variable quantity being a function of the horizontal stream line curvature. The magnitude of the vertical deflection should not trespass the contractual limit of the elasticity of the metal, surpassing which the metal would tend to corrugate or buckle. This limit as was mentioned above is guided by the curvature of the vessel at the point at which the plate is to be applied, and it will be understood that the exact area to which each plate must conform in order to define a certain curvature, may be readily calculated and by means of such calculations, the intersecting rib members may be arranged to form spaces which will admit the use of plates having a maximum area. Such calculations are however a matter of the ship design which will

no doubt be apparent to those familiar with this art.

As an example of such calculations, however, it may be proven practically and theoretically that the following equations coordinate the variable quantities mentioned above establishing the limit of the possible vertical elastic deflection of a plate without corrugation:

$$(1) \left(D/2 + \left(\frac{L}{2} \right)^2 \times \frac{l}{2D} \right) \times C = d$$

$$(2) b^2 + 4d^2 - 300 td > 0$$

b =vertical width of plate

l =horizontal length of plate

D =maximum horizontal deflection of plate

d =maximum vertical deflection of plate

t =thickness of plate

C =constant dependent upon the elasticity of the plate material

The length L may represent either one or a plurality of spans between the transverse frames. The thickness of the plates " t " is determined in accordance with Lloyds Regulations. The maximum longitudinal deflection D for the assumed length of plate " L " is determined from the boat offsets whatever the design may be. The constant C is calculated from the following equation:

$$C = .75 \times \frac{Y}{E} \times \frac{h}{s}$$

in which:

Y =yield point of the metal used

E =coefficient of elasticity of the metal

h =
maximum allowable stress
ultimate strength

After the values of " L ", " D " and " C " have been determined, the value of d may be calculated by substitution in Equation 1. From the value of d thus computed the value of " b " is found from table of the boat offset, whatever the design may be.

Formula 2 is used to check the validity of the above obtained values with reference to the thickness of the particular plate section being used. The minimum allowable thickness " t " may be obtained from any standard hand book such as Lloyds or the United States Shipping Bureau Regulations. In case the values of " d " and " b " found from Equation 1 do not satisfy Equation 2, the assumed length " L " must be taken shorter by one or more spans between the transverse frames so that the new values of " d " and " b " will satisfy Equation 2.

In the usual practice of my invention I employ a few main longitudinals running the entire length of the ship. If the value " b " found from the value of " d " calculated from Equation 1 above, for any particular cell, or area between longitudinals and ribs at one section, is found to be less than the

distance between the main longitudinals at this point, one or more supplementary longitudinals must be positioned between the main longitudinals to bring the area of the cell down to a point at which the desired curvature can be obtained without buckling or corrugating the plates.

In welding the plates to the mentioned rib members, it will be understood that the plates are provided with a dual weld such as is indicated in Figs. 5 and 6, in which the plates indicated by reference numerals 21 and 21', are illustrated as being welded to the transverse ribs 13 at the points indicated by reference numeral 23 and the edge of each plate is attached to an adjoining plate and to the transverse rib by a second weld indicated by reference numeral 24'. In a like manner the plates 21 and 21'' are attached to the longitudinal ribs 19 by the welding indicated at 25 and the edges of these adjoining plates are attached to each other and to the longitudinal ribs by means of a center weld 24'.

It will be understood that while I have herein described this process as applied to one particular form of small craft, the dimensions and arrangement of the members may of course be varied depending upon the design and size of the vessel, and while I have described one application of this method, the same is not limited to the specific illustration, but includes within its scope such adaptations as may come within the spirit of the appended claims.

I claim as my invention:

1. A method of constructing metal boats which includes: the formation of curved transverse ribs by cutting such ribs from substantially flat plates; providing said transverse ribs with aligned recesses; welding said ribs in spaced relation with each other to a keel; placing longitudinal ribs upon said transverse ribs by cold bending substantially straight metal bars into said aligned recesses and welding thereto to form a frame work; and plating said frame work by cold pressing flat metal plate sections into engagement with said ribs and welding said plate sections to said ribs, said transverse ribs and said longitudinal ribs being so positioned that the plates may be cold bent into engagement therewith without buckling.

2. A method of constructing metal boats which includes: the formation of curved transverse ribs by cutting such ribs from substantially flat plates; providing said transverse ribs with aligned recesses; welding said ribs in spaced relation with each other to a keel; placing longitudinal ribs upon said transverse ribs by cold bending substantially straight metal bars into said aligned recesses and welding thereto to form a frame work; and plating said frame work by cold pressing flat metal plate sections into engagement with said ribs and welding said plate sections

to said ribs and welding the edges of said plate sections to the edges of adjacent plate sections, said transverse ribs and said longitudinal ribs being so positioned that the 5 plates may be cold bent into engagement therewith without buckling.

3. A method of constructing metal boats which includes: providing transverse ribs with aligned recesses; welding said ribs to a 10 keel in spaced relation with each other; mounting longitudinal ribs upon said transverse ribs by cold bending substantially straight metal bars into said aligned recesses and welding thereto to form a frame work; 15 and plating said frame work by pressing substantially flat metal plate sections into engagement with said ribs and welding the edges of said plate sections to said ribs, said transverse ribs and said longitudinal ribs 20 being so positioned that the plates may be cold bent into engagement therewith without buckling.

4. A method of constructing metal boats which includes: providing transverse ribs 25 with aligned recesses; welding said ribs to a keel in spaced relation with each other; mounting longitudinal ribs upon said transverse ribs by cold bending substantially straight metal bars into said aligned recess 30 and welding thereto to form a frame work; and plating said frame work by pressing substantially flat metal plate sections into engagement with said ribs and welding the edges of said plate sections to said ribs, and 35 to the edges of adjacent plate sections, said transverse ribs and said longitudinal ribs being so positioned that the plates may be cold bent into engagement therewith without buckling.

40 5. A method of constructing metal boats which comprises: building a framework consisting of a plurality of transverse and longitudinal ribs arranged to form a plurality of cell spaces; cold bending flat metal 45 plate sections into positions such that the edges of said plate sections engage the ribs defining said cells; and attaching the edges of said plates to said ribs, the area of said plates being such that the vertical deflection of said 50 plates resulting from said cold bending does not trespass the contractual limit of the elasticity of the metal.

In testimony whereof, I have hereunto set my hand at Los Angeles, California, this 9th 55 day of July, 1928.

DIMITRI LIAMIN.
